AUTOMATIC RAILROAD TRACK GAUGE

Filed Nov. 9, 1948

Fig. 1.

UNITED STATES PATENT OFFICE

2,507,896

AUTOMATIC RAILROAD TRACK GAUGE

Le Van A. Frank, Freeport, Ill.

Application November 9, 1948, Serial No. 59,048

1 Claim. (Cl. 33—144)

1

This invention relates to gauge devices, and more particularly to a device for ascertaining deviations from correct gauge of the opposite rails of railroad tracks.

A main object of the invention is to provide a novel and improved railroad track device which is simple in construction, automatic in operation and which is not affected by side swaying of the vehicle to which the gauge device is attached.

A further object of the invention is to provide an improved automatic railroad track gauge device of the type which is attached to a track inspection vehicle and drawn along the track by said vehicle, the gauge device providing graduated signal indications of predetermined degrees of deviation of the tracks from correct gauge width, said device being sturdy in construction, reliable in performance and inexpensive to build.

Further objects and advantages of the invention will become apparent from the following description and claim, and from the accompanying drawings, wherein:

Figure 1 is a top plan view of a track inspection vehicle having connected thereto an automatic track gauge device constructed in accordance with the present invention.

Figure 2 is an enlarged detail bottom plan view of the track-engaging portion of the gauge device of Figure 1.

Figure 3 is an enlarged fragmentary cross-sectional view taken on line 3—3 of Figure 1.

Figure 4 is an enlarged cross-sectional detail view taken on line 4—4 of Figure 2.

Figure 5 is an enlarged cross-sectional detail view taken on line 5—5 of Figure 1.

Figure 6 is a schematic wiring diagram of the electrical indicating circuit employed in the track gauge device of Figure 1.

Referring to the drawings, 11 designates a conventional motor car of the type employed for inspecting railroad tracks. Secured to the rear transverse frame element 12 of the car by means of hinges 13, 13 are the rearwardly extending bar members 14, 14 and movably connected to the rear ends of bars 14, 14 by means of shoudered bolts 15, 15 extending through transverse slots 16, 16 formed in the bars 14, 14 is a cross-bar 17. As shown in Figures 1 and 3, a bracket member 18 is secured to the underside of cross-bar 17 extending at right angles thereto. Journalled in bracket member 18 are the respective vertical rollers 19, 19 adapted to ride on the top of the head of one of the rails, shown at 20. Secured to the underside of cross-bar 17 inwardly 55

2

adjacent bracket 18 is a second bracket member 21 having downwardly inclined arms 22, 22 provided at their ends with horizontal rollers 23 engageable with the inside vertical surface of the head of rail 20. Secured to the underside of the opposite end portion of cross-bar 17 is a bracket 24 in which is journalled a vertical roller 25 adapted to ride on the top of the head of the remaining rail 26.

10 Secured to the underside of cross-bar 17 inwardly spaced from bracket 24 and extending parallel to the rail 26 and at right angles to cross-bar 17 is an elongated block member 27. Pivoted to the underside of block member 27 at longitudinally spaced points thereon, shown respectively at 28, 29, 30 and 31 are the respective arms 32, 33, 34 and 35, having journalled to their outer ends the respective horizontal rollers 36, 37, 38 and 39. The inner ends of arms 32, 33, 34 and 35 are connected to block 27 by springs 40, biasing the arms clockwise, as viewed in Figure 2, whereby the rollers 36, 37, 38 and 39 are biased into engagement with the inside vertical surface of the head of rail 26. Secured to the underside of the block 27 and located to the right of the inner ends of the respective arms 32, 33, 34 and 35, as viewed in Figure 2, are the respective normally open push button switches 41, 42, 43 and 44 with their button elements located so as 20 to be engageable by the arms responsive to clockwise rotation thereof. The spacing of the push button switches from the respective arms is different for each arm so that each switch will be closed responsive to a different degree of rotation of the arm associated therewith.

As shown in Figures 1 and 3, the cross-bar 17 is connected to the arms 14, 14 by respective springs 45, 45, biasing the cross-bar 17 to the right as viewed in Figure 3, whereby rollers 23 30 are maintained constantly in rolling contact with the inside vertical surface of the head of rail 20. Any deviation in gauge between rails 20 and 26 will therefore cause the arms 32, 33, 34 and 35 to be rotated by their biasing springs to a degree 45 determined by the amount of gauge deviation.

Mounted on the car 11 is a panel 46 carrying respective signal lamps 47, 48, 49 and 50. As shown in Figure 6, these lamps are connected in respective series circuits with the switches 41, 42, 50 43 and 44, these circuits being connected in parallel across a storage battery 51, carried by the car 11. The wires leading from the switches are incorporated in a cable 52 extending from block 27 to the panel 46.

In operation, the device is drawn along the

tracks by the car 11. The hinge connections 13, 13 allow the arms 14 to angle freely in a vertical plane in response to vertical irregularities of the track without disengaging the rollers from the heads of the rails 20 and 26. Deviations in gauge width between the track rails will be indicated by the illumination of the respective signal lamps 47, 48, 49 and 50, each lamp representing a predetermined degree of gauge deviation. By observing the lamps, the deviations in gauge between the rails may readily be detected as the car 11 moves along the tracks and the amount of deviation may be readily determined by observing which of the lamps are illuminated.

The arms 32, 33, 34 and 35 may be located with respect to their associated switches to signal deviations over gauge width in successive increments, for example deviations of one quarter inch, one half inch, three quarters of an inch, and one inch, respectively.

While a specific embodiment of a railroad track gauge indicating device has been disclosed in the foregoing description, it will be understood that various modifications within the spirit of the invention may occur to those skilled in the art. Therefore it is intended that no limitations be placed on the invention except as defined by the scope of the appended claim.

What is claimed is:

A railroad track gauge device of the character described comprising a frame, means hingedly connecting said frame behind a track car for free movement vertically, said frame having a cross member movably secured thereto for movement transversely of the frame, guide means

fixedly secured to said cross member and engaging the top and inside surface of one of the track rails, spring means acting between the cross member and the remainder of the frame biasing said guide means outwardly against said one track rail, a plurality of follower members pivotally connected to said cross member and engageable with the inside surface of the opposite track rail, spring means biasing said follower members against said opposite track rail, respective normally open switches carried by the cross-member adjacent the respective follower members and closable thereby responsive to outward following movement of said respective follower members, said switches being differently spaced from the respective follower members to represent various predetermined degrees of track gauge deviations, and separate electric signal circuits controlled by the respective switches.
